UNITED STATES PATENT OFFICE.

JOHN K. YOUNG, OF PHILADELPHIA, PENNSYLVANIA.

DOOR-CHECK.

1,074,151.

Specification of Letters Patent. Patented Sept. 30, 1913.

Application filed October 29, 1912. Serial No. 729,410.

To all whom it may concern:

Be it known that I, JOHN K. YOUNG, a citizen of the United States, residing at Philadelphia, in the county of Philadelphia 5 and State of Pennsylvania, have invented certain new and useful Improvements in Door-Checks, of which the following is a specification.

This invention relates to an improvement 10 in a door check, and more specifically to means for positively holding the door in open position and rigidly against movement. To this end I provide a simple, highly efficient, and inexpensive device for readily 15 checking the door against a wall or similar abutment, and the arrangement contemplates a structure yielding before the advances of the door without causing any frictional noise or chattering, as is the case 20 with many present devices.

With this and other objects in view my invention consists in the arrangement, combination and details of construction herein disclosed, and then more particularly 25 pointed out in the appended claims.

In the drawings, Figure 1 is a side sectional elevation of my device which is composed of two co-operating members, Fig. 2 is a view similar to Fig. 1 showing the check 30 member in operation for engaging the holding or securing member, Fig. 3 is a vertical elevation of the check holding member, Fig. 4 is a vertical elevation of the front of the holding member, and Fig. 5 is a bottom plan 35 view of the checking member.

Reference being made to the drawings, wherein similar reference characters designate similar parts wherever used, a wall or similar abutment is shown at 1 to which 40 is fastened a bearing block 2 having a forwardly projecting socket 3, preferably tapering as shown, in which socket is pivoted on a stud 6 a yielding holding member composed of sides 4 and 5 and centrally 45 raised surface 7 formed at its forward end with an upwardly sloping wall 8 terminating in a concave portion terminating in the shoulder 9. A highly polished roller 11 is pivoted at 10 to the raised surface 7 which 50 is arranged to engage the checking member, as the door is swung into full open position, and thereafter serves to prevent accidental displacement of the check from its position thereover. At the extreme rear 55 end of the raised wall 7 is formed a suitable recess receiving a coiled spring having one

end bearing against the inner wall of said recess and the opposite end bearing against the inner wall of the bearing block 2. The rear of the holding member is formed with 60 a downwardly sloping or inclined side 7', and the bearing block, as shown in Fig. 3, is formed with an opening member to be satisfactorily true in position, and the normal position of the holding member will 65 be determined by the coiled spring 12, and as shown in Figs. 1 and 2, it will be held in a substantially horizontal position with respect to the vertical.

The checking member is very simple in 70 its construction and is composed of a bearing block 15 suitably secured upon the back of a door 14; the block 15 carries a forwardly projecting check which is of the shape shown in Figs. 1 and 2, consisting of 75 an extreme forward portion correspondingly inclined with respect to the inclined wall 8 of the holding member, intermediate the ends of the check, and is in continuation of a convex surface 16', completing the 80 under surface of the said latch. The parts are in normal position as shown in Fig. 2, but the door 14 has been moved a sufficient extent to cause the forwardly inclined face of the check to bear upon the polished roller 85 11, but without sufficient stress to cause the holding member to be depressed. In operation the door will be continuously impelled so that the inclined under face of the check 16 shall rise over and pass said roller and 90 thereby cause the convex surface 16 of the check to engage the roller 11, as shown in Fig. 1. As the holding member is formed with an inclined rear face 7' there will be normally some clearance between the inner 95 wall of the block 2 and said wall 7', the spring 12 urging the holding member outwardly from the block 2; therefore, as the door is pushed to its fullest extent, and as the beveled or inclined face of the check 16 is brought in engagement with the polished roller 11 the holding member will, in consequence be depressed against the tension of the spring 12 as shown in dotted lines in Fig. 2 until the bevel wall of 7' approximately overlies the wall of the block 2. The shoulder 17 intervening between the beveled wall of the check and the convex surface thereof will, when the check is in locked position, occupy a position substantially in 110 line with the axis of the roller 11, thereby preventing the accidental displacement of

the door, and the holding member will then be restored to normal position, and the latch will be held locked as shown in Fig. 1.

Various modifications of the details of construction may be resorted to without departing in essence from the arrangement herein disclosed.

I claim:

1. In combination a base, a channel member pivoted eccentrically thereof, a spring on said base adapted to hold said member normally in a horizontal position, said member being reduced at its outer end, a non flexible roller pivoted to said end, and a hook adapted to engage said roller and be held thereto.
2. In combination a base-plate, a channel

member fulcrumed eccentrically upon said base-plate, a spring carried by said base-plate holding said member in horizontal position, a depressed part being formed at the opposite end of said channel member, a roller fulcrumed in said depressed part, and a latching member having a beveled end arranged to depressingly ride over said roller and having a hook for holding it in locked position.

In testimony whereof I affix my signature in presence of two witnesses.

JOHN K. YOUNG.
